DESIGN FOR A WIRE FENCE

Frank A. Luebbe, Cincinnati, Ohio, assignor to Pittsburgh Steel Company, Pittsburgh, Pa., a corporation of Pennsylvania

Application May 4, 1938, Serial No. 76,975

Term of patent 14 years

To all whom it may concern:

Be it known that I, Frank A. Luebbe, a citizen of the United States, residing at Cincinnati, in the county of Hamilton and State of Ohio, have invented a new, original, and ornamental Design for a Wire Fence, of which the following is a specification, reference being had to the accompanying drawing, forming a part thereof.

In the drawing the single figure is an elevation of a section of wire fence showing my new design.

I claim:

The ornamental design for a wire fence, as shown.

FRANK A. LUEBBE.
